UNITED STATES PATENT OFFICE.

JULIAN H. KENDIG, OF PITTSBURGH, PENNSYLVANIA.

DESIGN FOR AN AUTOMOBILE-RADIATOR ORNAMENT.

53,371.

Specification for Design.

Patented May 27, 1919.

Application filed June 14, 1917. Serial No. 174,776. Term of patent 3½ years.

To all whom it may concern:

Be it known that I, JULIAN H. KENDIG, a citizen of the United States, residing at Pittsburgh, in the county of Allegheny and State of Pennsylvania, have invented a new, original, and ornamental Design for Automobile-Radiator Ornaments, of which the following is a specification, reference being had to the accompanying drawing, forming a part thereof.

Figures 1 and 2 are a plan view and front

elevation, respectively, showing the ornament in which my invention resides, and the dot and dash lines showing a conventional form of support for the ornament forming no part of my invention, and Fig. 3 is a perspective view of the ornament independent of the support.

I claim:

The ornamental design for an automobile radiator ornament, substantially as shown.

JULIAN H. KENDIG.
